WATER TOBOGGAN

Victor H. Hurt, Cranston, R. I., assignor to United States Rubber Company, New York, N. Y., a corporation of New Jersey.

Application January 7, 1943, Serial No. 471,539

9 Claims.

(Cl. 9—2)

This invention relates to a water toboggan constructed to be towed in the water or paddled by a person lying upon the toboggan, and more particularly to an inflated toboggan that is well adapted for both of these uses.

A primary feature of the present invention resides in the construction whereby the water toboggan is made reversible so that it is well adapted for towing purposes when one side is up and is well adapted to be paddled with the arms and hands when the opposite side is up.

To this end the toboggan is provided with two elongated pontoons or tubes which are retained in laterally spaced relation by a connecting apron that has a flexible upwardly inclined bow flap secured to the forward end portion of each tube. The connection between the apron, tubes and bow flap is such that when one side of the toboggan is up the pontoons will lie in spaced approximately parallel relation to each other so that a person may lie on the apron between the pontoons while the toboggan is being towed, and when the bow flap is reversed and the other side of the toboggan is up the pontoons will be held close together at their forward ends so that a person may rest the forward portion of his body on these pontoons while he paddles with his arms.

This desirable reversible feature of the toboggan is secured by gradually increasing the width of the bow flap over that of the apron, and by securing the side edges of the apron to the pontoons along straight lines, while the side edges of the bow flap are secured diagonally around the forward ends of the pontoons. As a result of this construction the bow flap may be turned up or down from the plane of the apron. When the flap is turned one way the forward ends of the pontoons will lie spaced from each other outside of the enclosure formed by the bow flap, and when the flap is turned in the opposite direction the forward ends of the pontoons will lie close together inside of the enclosure formed by the bow flap.

Another important feature of the invention resides in the construction whereby the forward ends of the tubes or pontoons are made chisel-shaped to provide flat wide blades disposed at right angles to the length of each tube. By attaching the forward ends of the bow flap to these blade-like ends near a side edge of each blade, a construction is secured whereby the forward edge of the bow flap is held well elevated out of the water when either side of the toboggan is up.

The above and other features of the present invention will be more fully understood from the

following description when read in connection with the accompanying drawings wherein:

Fig. 1 is a top plan view of the water toboggan as used by a person lying upon the same so that he may paddle with his arms and hands;

Fig. 2 is a side view of the construction of Fig. 1;

Fig. 3 is a sectional view taken on the line 3—3 of Fig. 1;

Fig. 4 is a front end view of Fig. 1;

Fig. 5 on a smaller scale is a bottom view of the construction of Fig. 1;

Fig. 6 is a top plan view of the toboggan as used for towing purposes with the pontoons well spaced throughout their length;

Fig. 7 is a side view of the construction of Fig. 6; and,

Fig. 8 is a front end view of Fig. 7.

In the embodiment of the invention illustrated in the drawings the entire water toboggan is or may be constructed of a rubberized fabric or other air impervious fabric. The buoyancy of the toboggan is supplied by the two inflated, elongated pontoons or tubes 10 and 11 which are retained in spaced relation to each other by the connecting apron 12. This apron has its width gradually increased near its forward end to form the bow flap 13.

The pontoons or tubes 10 and 11 are shown as slightly larger in diameter at the forward end of the toboggan than at the rear end as this serves to increase the buoyancy of the forward portion of the toboggan to better support the increased weight of the head and shoulders of the person using the toboggan. Each tube 10 and 11 in the construction shown is adapted to be air inflated and has the chisel-like rear ends 14 and 15 to provide flat wide blades disposed at right angles to the length of the tubes, and the tubes 10 and 11 have the similar chisel-shaped forward ends 16 and 17, which are somewhat wider than the ends 14 and 15.

The apron 12 is of uniform width throughout the major portion of its length and the side edges of this major portion are firmly secured to the tubes 10 and 11 along the seams 18 and 19. The forward end of the apron 12, as above stated, flares outwardly to provide the flap 13 of increased width. The side edges of this flap are secured along diagonal or spiral paths about the forward end portions of the tubes 10 and 11 by the seams 20 and 21. The arrangement is such that the outer end of the flap 13 is secured at its side edges to the chisel-shaped ends 16 and 17 near a side edge of the wide chisel blades,

The purpose of this is to hold the forward edge of the flap 13 well elevated above the water when either side of the toboggan is turned up. In this manner a construction is secured whereby the bow flap is held well elevated by these tubes when the bow flap is turned in either direction.

When the toboggan is reversed to change, for example, from the construction shown in Fig. 1 to that shown in Fig. 6, the tubes 10 and 11 so far as the rear portion of the toboggan is concerned will simply revolve through an angle of approximately 120° relatively to the seams 18 and 19 which secure the apron 12 to the tubes. A somewhat different action, however, occurs at the forward end of the toboggan during such reversal, since when the flap 13 is turned upwardly as shown in Fig. 1, the forward ends of the tubes 10 and 11 will lie inside of the enclosure formed by this bow flap with the blade-like ends 16 and 17 inclined to the floor formed by the apron 12. Whereas, when the bow flap is turned in the opposite direction and the tubes 10 and 11 are rotated through an angle of approximately 120°, the forward ends of these tubes will lie outside of the enclosure formed by the bow flap as shown in Figs. 6, 7 and 8, where it will be noted that the blade-like ends 16 and 17 extend upwardly in a vertical direction, as best shown in Fig. 8.

The bow flap 13 is shown as provided with the grommet 22 for towing purposes and the rear end of the apron 12 has the grommets 23. Each pontoon or tube is shown as having secured thereto several straps or hand loops 24 whereby the toboggan may be more easily handled, and the straps may be grasped to support a person in the water.

The pontoons 10 and 11 are shown as provided with the oral inflating tubes 25 which enter the pontoons at 26. Each tube 25 has a cap or valve 27 at its outer end which may be adjusted to one position to permit inflation of the pontoon and to a second position to prevent the inflating air from escaping through such tube. Each tube when not in use may be retained in place along the pontoon by the holding strap 28. The tubes 25 are so located that the pontoons may be readily inflated by the person lying upon the toboggan when either side is up. The pontoons 10 and 11 may be deflated by providing the valves 29 having the removable caps 30.

It will be seen from the foregoing that by making the water toboggan of the present invention reversible, one side may be turned up when the same is to be towed in the water so that the pontoons will lie a substantial distance from each other throughout their length to provide a clearance space therebetween for a person to lie upon the apron 12, and when the other side of the toboggan is up and the bow flap is reversed, the forward ends of the pontoons will be held close together to support the head and shoulders of a person using the toboggan well elevated above the water so that he will be in a more comfortable position to paddle with his arms and hands.

When the toboggan shown is not in use it may be deflated and rolled up into a compact package, and when inflated ready for use the pontoons may be quickly turned to a position in which their forward ends lie inside of the apron as shown in Fig. 4, or to a position in which these forward ends lie outside of the apron as shown in Fig. 8.

Having thus described my invention, what I claim and desire to protect by Letters Patent is:

1. A reversible water toboggan comprising two

inflated elongated pontoons retained in laterally spaced relation by a connecting apron that has an upwardly inclined bow flap, the toboggan being adapted when turned so that one face is up to provide space for a person to lie between the pontoons on the apron, and when turned so that the other face is up to hold the forward ends of the pontoons close together so that a person may lie on the pontoons to paddle with his arms.

10 2. A reversible water toboggan comprising two elongated pontoons retained in laterally spaced relation by a connecting apron that has an upwardly inclined bow flap, the pontoons being so connected by the apron and flap that when one face is turned up the pontoons will lie in spaced parallel relation and when the other face is turned up the pontoons will be held close together at their forward ends and diverge from each other rearwardly.

15 3. A reversible water toboggan comprising two elongated pontoons retained in laterally spaced relation by a connecting apron that has an upwardly inclined bow flap, the pontoons being so connected by the apron and flap that when one face is up the pontoons will lie a substantial distance apart with their forward ends outside of the enclosure formed by the bow flap, and when the other face of the toboggan is up the forward ends of the pontoons will lie close together and within said enclosure.

20 4. A reversible water toboggan comprising two elongated pontoons having chisel-shaped forward ends, an apron secured to the pontoons to hold them in laterally spaced relation and having an upwardly inclined bow flap attached to said chisel-shaped ends, whereby when the flap is turned up in one direction said ends will lie close together inside of the bow flap and when the flap is turned up in the opposite direction said ends will lie spaced apart outside of the bow flap.

25 5. A reversible water toboggan comprising two elongated pontoons having chisel-shaped forward ends, an apron secured to the pontoons to hold them in laterally spaced relation and having an upwardly inclined bow flap attached to said chisel-shaped ends near a side edge of each, whereby the bow flap will be supported by said ends so that its upper edge will lie near the plane of the upper face of the toboggan when either face is up.

30 6. A water toboggan comprising two elongated pontoons having chisel-blade forward ends, a connecting apron secured along the pontoons in the approximate longitudinal plane defined by the flattened blade portion of each forward end so that when the toboggan is in the water and a load rests upon one face of the apron the flattened blade ends will assume a vertical position, and a bow flap at the forward end of the apron and attached to the pontoons along inclined lines extending upwardly to the upper edge of the chisel blades.

35 7. A water toboggan comprising two elongated pontoons having chisel-shaped forward ends, an apron secured to the pontoons to hold them in laterally spaced relation and having an upwardly inclined bow flap that is attached to said chisel-shaped ends near a side edge of each, whereby the bow flap is supported by said ends so that its upper edge lies adjacent the upper plane of the toboggan.

40 8. A reversible water toboggan comprising two elongated pontoons retained in laterally spaced relation by a connecting apron that has a flexible

bow flap, the flap being so connected to the pontoons that it will extend upwardly in one direction when one side of the toboggan is up and may be reversed to extend upwardly in the opposite direction when the other side of the toboggan is up.

9. A reversible water toboggan comprising two elongated pontoons retained in laterally spaced relation by a connecting apron that has a flexible

bow flap, the flap being so connected to the pontoons that it will extend upwardly in one direction and hold the forward ends of the pontoons close together when one side of the toboggan is up, and may be reversed to extend upwardly in the opposite direction and hold the forward ends of the pontoons further apart when the other side of the toboggan is up.
